UNITED STATES PATENT OFFICE.

FRANK G. HOLMES, OF TRENTON, NEW JERSEY, ASSIGNOR TO LENOX, INC., OF TRENTON, NEW JERSEY, A CORPORATION OF NEW JERSEY.

DESIGN FOR A PLATE OR SIMILAR ARTICLE.

Application filed January 13, 1928. Serial No. 24,854. Term of patent 14 years.

To all whom it may concern:

Be it known that I, FRANK G. HOLMES, a citizen of the United States, and resident of Trenton, county of Mercer, and State of New Jersey, have invented a new, original, and ornamental Design for a Plate or Similar Article, of which the following is a specification, reference being had to the accompanying drawing, forming part thereof, which

drawing is a face view of a plate or similar article, illustrating my new design, the dot and dash lined segment indicating that the design therein is to be repeated around the rim of the plate.

I claim:

The ornamental design for a plate or similar article, as shown, and described.

FRANK G. HOLMES.
